MEINHARDT, OF NEW YORK, N. Y.

INTERNAL-COMBUSTION ENGINE.

1,213,315.

Specification of Letters Patent. Patented Jan. 23, 1917.

Application filed July 9, 1913. Serial No. 778,075.

To all whom it may concern:

Be it known that I, Hugo C. WELL, a subject of the Emperor of Germany, and a resident of the city of New York, borough of the Bronx, in the county and State of New York, have invented a new and Improved Internal-Combustion Engine, of which the following is a full, clear, and exact description.

10 My invention has for its object to provide an internal combustion engine, having a piston with two scavenger ports, and provided with a valve for rotating on the piston for opening and closing the ports, a 15 beveled gear being secured to the valve with which meshes a beveled gear mounted coaxially with a piston rod and operated thereby.

Another object of the invention is to prevent the movement of the valve in one direction, so that the valve will have intermittent rotary movement in the opposite direction.

Still another object of the invention is to 25 provide the valve with a rim having a port, which periodically affords communication to the interior of the cylinder from an inlet port in the cylinder.

Additional objects of the invention will 30 appear in the following complete specification, in which the preferred form of the invention is disclosed.

In the drawings similar characters of reference indicate corresponding parts in all the views, in which—

Figure 1 is a sectional view of a four-cycle engine, on the line 1—1 of Fig. 2; Fig. 2 is a sectional view on the line 2—2 of Fig. 1; Fig. 3 is an enlarged sectional view on the line 3—3 of Fig. 1; Fig. 4 is a sectional view on the line 4—4 of Fig. 3; Fig. 5 is a fragmentary sectional view, showing a ratchet wheel secured to the stud, and a pawl for co-operating with the ratchet wheel; Fig. 6 is a fragmentary sectional view showing the means by which the beveled gear mounted coaxially with the piston rod is operated thereby; Figs. 7, 8 and 9 are diagrammatic views showing the different 45 positions of the valve; Fig. 10 is a sectional elevation of the invention as applied to a two-cycle engine; and Figs. 11, 12, 13 and 14 are diagrammatic views showing the position of the valve illustrated in the two-cycle engine shown in Fig. 10 of the drawings.

Certain features shown in the drawings and described in this specification are claimed in my co-pending application having Serial No. 25,298.

By referring to the drawings it will be seen that the cylinder 5 is provided with a piston 6, this piston 6 having scavenger ports 7 and 8, the scavenger ports 7 and 8 having communication with the passages 9 and 10 which are adapted to communicate with the scavenger ports 11 and 12 in the cylinder. The piston 6 has aprons 13 and 14, the apron 13 being adapted to close the scavenger ports 11 when the piston 6 is in the position shown in Fig. 1 of the drawings, and the apron 14 also substantially closing the scavenger ports 12 when the piston 6 is in the said position.

A pipe 15 communicates with the scavenger ports 11, for forcing air therethrough, and to the interior of the cylinder through the passage 9 and the scavenger port 7 when the piston valve 16 is in the position shown in Figs. 7 and 8 of the drawings. This 75 valve 16 is mounted for rotating on the piston 6, the valve 16 being secured to a stud 17, which is journaled in a bearing 18 in the piston 7. To this stud 17 there is secured a ratchet wheel 19, which is engaged by a pawl 20, pivoted to the under side of the piston, and held in operative position by the spring 21 in the customary manner. There is also secured to this stud 17 a beveled gear wheel 22, with which meshes a beveled gear wheel 23, mounted loosely on a pin 24 mounted in the piston. The upper end of the piston rod 25 is also mounted on this pin 24, and secured to the piston rod 25 there is a member 26, having pawls 27, which are adapted to engage the beveled gear wheel 23, at the recesses 28, therein. As shown in Fig. 6 of the drawings, the recesses 28 are not large enough to permit of the complete entrance of the hooks 29 on 100 the pawls 27. These pawls permit the member 26 with the piston rod 25 to move in one

direction relatively to the beveled gear wheel 23, the hooks 29 on the pawls 27 engaging the beveled gear wheel 23 at the recesses 28 to secure a rotary movement of the beveled gear wheel 23 when the member 26 and the piston rod 25 move in the opposite direction.

In the cylinder 5 there is an inlet port 30, and the valve 16 has a rim 31, with two ports 32 for communicating with the inlet port 30 in the cylinder 5. The valve 16 also has two scavenger ports 33 for communicating with the scavenger ports 7 and 8 in the piston 6.

Fig. 2 of the drawings shows the position of the valve at the firing stroke. Fig. 7 shows the position of the valve at the end of the firing stroke, and the commencement of the scavenger stroke. Fig. 8 shows the position of the valve at the end of the scavenger stroke and the commencement of the inlet stroke, and Fig. 9 shows the position of the valve at the commencement of the compression stroke.

It will be seen that the valve 16 makes a one-quarter revolution with each complete rotation of the shaft 34, which is connected with the piston rod 25, by means of the crank 35. This rotary movement of the piston 16 is obtained by means of the relative sizes of the beveled gear wheels 22 and 23. The piston rod 25 on the firing stroke shown in Fig. 2 of the drawings rotates, by the means described, the beveled gear 23, sufficiently far for this beveled gear 23 through the beveled gear 22, to rotate the stud 17, a distance sufficient to move the valve to the position shown in Fig. 7, at which point the scavenger ports 33 in the valves 16 are in communication with the scavenger ports 7 and 8 in the pistons 6, these scavenger ports 7 and 8 being elongated as shown in Figs. 7, 8 and 9 of the drawings. With the upward movement of the piston 6 the valve 16 is moved by the means described to the position shown in Fig. 8 of the drawings, and with the downward or inlet stroke of the engine, the valve 16 is moved from the position shown in Fig. 8 of the drawings to the position shown in Fig. 9 of the drawings, at which point one of the inlet ports 32 has been brought into engagement with the inlet port valve 30, permitting the explosive mixture to flow therethrough, and into the cylinder, so that with the upward movement of the piston on the compression stroke the combustible mixture will be compressed to be fired in a manner readily understood.

In the two-cycle type of engine, shown in Fig. 10 of the drawings, the piston 36 corresponds with the piston 6 shown in Fig. 1 of the drawings, and the inlet port 37 in the cylinder, the scavenger ports 38 and 39 in the cylinder and the scavenger ports 40

and 41 in the piston corresponding with the similar inlet and ports shown in Fig. 1 of the drawings. The valve 45 has a rim 42, with a valve port 45^a. The two-cycle engine shown in Fig. 10 of the drawings has a stud 43, which is journaled in the bearing 44, in the piston 36, the valve 45 being secured to the upper end of the stud 43 and a beveled gear wheel 46 being secured to the lower end of the stud 43. This beveled gear wheel 46 is in mesh with a beveled gear wheel 47 secured for rotating at all times with the upper terminal 48 of the piston rod 49, which is articulated to the piston 36 in the customary manner. It will, therefore, be seen that with this construction the valve 45 will rock with the rotation of the shaft 50, and that it will not rotate in the same direction intermittently, as is the case with the construction shown in Fig. 1 of the drawings.

In the diagrammatic view shown in Fig. 11, which is the firing position, the scavenger ports 51 in the valve 45 are disposed at a distance from the elongated scavenger ports 40 and 41 in the piston 36, but with the downward movement of the piston 36 under the influence of the charge the valve 45 will rotate to the position shown in Fig. 12 of the drawings, when the scavenger ports 51 in the valve 45 will be in communication with the scavenger ports 40 and 41 in the piston 36, to permit a blast of air to flow through the ports 38, the port 40, one of the ports 51, through the cylinder to the port 51, through a port 41, and out of the ports 39. This will carry the valve 45 as far as it will travel in one direction, and with the movement of the valve in the opposite direction it will be passed to the position shown in Fig. 13 of the drawings, at which point the piston is at its lowermost position, to permit the admission of an explosive mixture through the port 37, and the valve port 45^a, the valve 45 continuing to rotate in the last-mentioned direction with the upward movement of the piston and with the compression of the combustible mixture so that when the piston has moved to its uppermost position the ports 51 in the valve 45 will be disposed as shown in Fig. 11 of the drawings at which point the explosive mixture will be fired.

It will be understood that both forms of the engine may be reversed.

Having thus described my invention I claim as new and desire to secure by Letters Patent:

1. In an internal combustion engine, a cylinder having a port, a piston for reciprocating in the cylinder, and having a port for communicating with the port of the cylinder, a valve mounted for rotating on the piston for commanding the second-mentioned port, a piston rod fulcrumed to the 125

piston, and gearing connecting the piston rod with the valve for rotating the latter.

2. In an internal combustion engine, a cylinder having a port, a piston for reciprocating in the cylinder and having a port for communicating with the port in the cylinder, a valve mounted for rotating on the piston for commanding the second-mentioned port, a piston rod fulcrumed to the piston, a beveled gear secured for rotating with the valve, a second beveled gear meshing with the first beveled gear, and means by which the second beveled gear is operable by the piston rod.

3. In an internal combustion engine, a cylinder having a port, a piston for reciprocating in the cylinder and having a port for communicating with the port in the cylinder, a valve for commanding the second-mentioned port and mounted for rotating on the piston on an axis extending longitudinally of the cylinder, a beveled gear secured for rotating with the valve, a piston rod fulcrumed to the piston on an axis extending transversely of the cylinder, a beveled gear meshing with the first beveled gear, and means operable by the piston rod for actuating the second mentioned beveled gear.

4. In an internal combustion engine, a cylinder having a port, a piston for reciprocating in the cylinder, and having a port for communicating with the port of the cylinder, a valve mounted for rotating on the piston for commanding the second-mentioned port, a piston rod fulcrumed to the piston, gearing connecting the piston rod with the valve for rotating the latter, and a pawl and ratchet means to prevent the rotation of the valve in one direction.

5. In an internal combustion engine, a cylinder having a port, a piston for reciprocating in the cylinder and having a port for communicating with the port in the cylinder, a valve mounted for rotating on the piston for commanding the second-mentioned port, a piston rod fulcrumed to the piston, a beveled gear secured for rotating with the valve, a second beveled gear meshing with the first beveled gear, means by which the second beveled gear is operable by the piston rod, and means to prevent the rotation of the valve in one direction relatively to the piston.

6. In an internal combustion engine, a cylinder having a port, a piston having a central opening and a port for communicating with the first port, a stud journaled in the opening, a valve for commanding the port in the piston disposed at one side of the piston and secured for rotating with the stud, a ratchet wheel disposed at the other side of the piston and secured for rotating with the stud, a pawl on the piston for co-operating with the ratchet wheel, a beveled

gear secured to the stud, a beveled gear meshing with the first beveled gear, a piston rod articulated to the piston, and means by which the piston rod is adapted to operate the second beveled gear.

7. In an internal combustion engine, a cylinder having a port, a piston having a central opening and a port for communicating with the first port, a stud journaled in the opening in the piston, a valve disposed at one side of the piston and secured for rotating with the stud, a ratchet wheel secured for rotating with the stud, a pawl on the piston for co-operating with the ratchet wheel, a beveled gear secured to the stud, a pin disposed transversely of the piston and secured thereto, a beveled gear with recesses meshing with the first beveled gear, and mounted on the pin, a piston rod mounted on the pin for rocking relatively to the piston and the second beveled gear, and a member secured to the piston rod and having pawls for engaging the second beveled gear at the recesses for rotating the second beveled gear when the piston rod rocks in one direction.

8. In an internal combustion engine, a cylinder having a port, a piston having a central opening and a port for communicating with the first port, a stud journaled in the opening in the piston, a valve disposed at one side of the piston and secured for rotating with the stud, a beveled gear secured to the stud, a pin disposed transversely of the piston and secured thereto, a beveled gear with recesses meshing with the first beveled gear and mounted on the pin, a piston rod mounted on the pin for rocking relatively to the piston and the second beveled gear, and a member secured to the piston rod and having pawls for engaging the second beveled gear at the recesses, for rotating the second beveled gear when the piston rod rocks in one direction.

9. In an internal combustion engine, a cylinder having a port, a piston for reciprocating in the cylinder and having a port for communicating with the port in the cylinder, a valve for rotating on the piston for opening and closing the second-mentioned port, a beveled gear on the valve, a piston rod fulcrumed to the piston, and a beveled gear secured for moving the piston rod and meshing with the first beveled gear for rocking the valve for the purpose specified.

10. In an internal combustion engine, a cylinder having an inlet port, and two scavenger ports, a piston for uncovering the inlet port at predetermined periods in the movement of the piston, and provided with two scavenger ports in the cylinder, a valve rotating on the piston for opening and closing the scavenger ports therein, a beveled gear secured to the valve, a piston rod fulcrumed to the piston, and a beveled gear se-

cured for moving with the piston rod and meshing with the first beveled gear for rocking the valve for the purpose specified.

11. In an internal combustion engine, a cylinder having an inlet port and two scavenger ports, a piston having a central opening, two scavenger ports for communicating with the scavenger ports in the cylinder, and a rim with two inlet ports, a stud journaled 5 in the opening in the piston, a valve disposed at one side of the piston and secured for rotating with the stud, a ratchet wheel secured for rotating with the stud, a pawl on the piston for coöperating with the 10 ratchet wheel, a beveled gear secured to the stud, a pin disposed transversely on the piston and secured thereto, a beveled gear with recesses meshing with the first beveled gear and mounted on the pin, a piston rod 15 mounted on the pin for rocking relatively to the piston and the second beveled gear, and a member secured to the piston rod and having pawls for engaging the second beveled gear at the recesses therein, for rotating the 20

second beveled gear when the piston rod 25 rocks in one direction.

12. In an internal combustion engine, a piston having a central opening and a port, a stud journaled in the opening, a valve for commanding the port in the piston and disposed at one side of the piston, the valve being secured for rotating with the stud, a ratchet wheel disposed at the other side of the piston and secured for rotating with the stud, a pawl on the piston for coöperating 30 with the ratchet wheel, a gear secured to the stud, a gear meshing with the first mentioned gear, a piston rod articulated to the piston and means by which the piston rod is adapted to operate the second mentioned 35 gear.

In testimony whereof I have signed my name to this specification in the presence of two subscribing witnesses.

HUGO C. WELL.
